UNITED STATES PATENT OFFICE.

WILLIAM LOEFFLER, OF BLADENSBURG, MARYLAND.

CURTAIN AND SHADE SUPPORTING BRACKET.

1,280,053.

Specification of Letters Patent. Patented Sept. 24, 1918.

Application filed May 14, 1918. Serial No. 234,388.

To all whom it may concern:

Be it known that I, WILLIAM LOEFFLER, a citizen of Germany, residing at Bladensburg, Maryland, have invented certain new and useful Improvements in Curtain and Shade Supporting Brackets, of which the following is a specification.

This invention relates to improvements in curtain and shade supports and it is the 10 principal object of the invention to provide a support capable of being easily and quickly attached to the frame of a window for supporting the usual curtain pole and shade brackets in proper positions without 15 defacing the frame and also allowing the ready removal thereof when necessary.

Another and equally important object of the invention is to provide a support of the character mentioned which can be adjusted 20 for use in connection with window frames differing in size.

The foregoing together with additional advantageous details and arrangement of parts of the preferred embodiment of my invention will be clear from the specific description hereinafter contained, when read 25 in connection with the accompanying drawings forming part thereof, wherein said embodiment of the invention is illustrated 30 for the purpose of facilitating a full understanding of the present improvements.

In the drawings:

Figure 1 is a fragmentary front elevation of a window frame having my improved 35 support engaged therewith.

Fig. 2 is a horizontal section therethrough showing one of the brackets partly in section,

Fig. 3 is a detail in side elevation of one 40 of the plates and the brackets carried thereby,

Fig. 4 is a horizontal section through one of the plates,

Fig. 5 is a detail in perspective of one of 45 the shade supporting brackets, and

Fig. 6 is a fragmentary detail in section showing the adjusting connection of the adjustable rod.

Having more particular reference to the 50 drawings, in connection with which like reference characters will designate corresponding parts throughout the several views, 1 represents a portion of a window frame to which the improved support is attached, 55 said support including right angularly

formed plates 2 formed of metal or other suitable material and having curved arms 3 extending from certain of their marginal portions which arms have the usual curtain pole supports 4 riveted or otherwise secured 60 thereto as at 5 while the upper ends of said supports are similarly engaged with the adjacent ends of curved bracing strips 6 having their lower ends engaged with the upper portions of the several plates 3 as at 7. 65

Secured to the adjacent sides of the several plates are bearing cups 8 which receive therein ball members 9, one of said members being carried on the outer ends of screw-threaded rods 11 arranged in the tubular elements 10, thus completing the adjustable rod whereby said plates can be positively engaged with the adjacent sides of the window frame 1. As will be noted, the adjacent ends of the tubular members are hingedly connected as at 12, said ends being formed to prevent movement of the same in one direction, for an obvious purpose. To retain the ball members 9 in position in their respective cups 8 semi-spherical closure caps 13 are engaged with the opposite ends of the adjustable rod and with the adjacent marginal portion of said cups. Thus, to engage the brackets with the opposite sides of a window frame the adjustable rod 80 is first adjusted to correspond to the space occurring therebetween by means of adjusting nuts 14 which are arranged on the screw-threaded rods 11 and retained in yoke members 15 having one end connected to the 85 adjacent end of one of the tubular members composing the adjustable rod.

With the rod properly adjusted, the same is then positioned between the sides of the window frame 1 and spread by moving the 95 hinged intermediate portion thereof inwardly, thus engaging the plates 2 with the adjacent portions of the window frame sides.

Brackets 16 are engaged with the adjacent portions of the angle plates 2 and are provided with bearing openings conforming in shape to the usual trunnion provided shade rollers now commonly used such as indicated by the numeral 17, these brackets, obviously, being particularly adapted for use 100 in connection with shades which are positioned between the opposite sides of a window frame.

Secured to the outer sides of the angle plates 2 are corrugated strips 18, the cor- 110

rugations therein forming a plurality of pockets into which the bearing pintles 19 carried by brackets 20 may be passed, said brackets having the usual trunnion receiving seat formed in their outer ends. As will be noted, these brackets can be adjusted to receive shade rollers varying in length by properly positioning the bearing pintles 19 thereof in certain of the pockets formed by 10 the corrugated strips.

Manifestly, the construction shown is capable of considerable modification and such modification as is within the scope of my claims, I consider within the spirit of my 15 invention.

I claim:

1. A support of the character described including angle plates having laterally disposed arms forward on the outer marginal portions thereof, pole supports secured to said arms, an adjustable rod engaged at its opposite ends with said plates, corrugated strips secured to the outer portions of said plates, brackets receivable in the pockets formed by said corrugated strips, and other

brackets secured to the inner portions of said plates.

2. A support of the character described including a pair of angle plates having laterally disposed arms formed on the outer portions thereof, pole supports secured to said arms, a hinged sectional rod swivelly connected at its opposite ends to said plates, and means engaged with one of the rod sections for causing expansion thereof. 30

3. A support of the character described including a pair of angle plates having laterally disposed arms formed on the outer marginal portions thereof, pole supports secured to said arms, a hinged sectional rod 40 swivelly connected at its opposite ends to said plates, means engaged with one of the rod sections for causing expansion thereof, brackets adjustably connected to the plates, and other brackets secured to the inner portions of said plates. 45

In testimony whereof, I affix my signature hereto.

WILLIAM LOEFFLER.

Copies of this patent may be obtained for five cents each, by addressing the "Commissioner of Patents, Washington, D. C."
